UNITED STATES PATENT OFFICE.

PIETRO AMEGLIO, OF GENOA, ITALY.

ELECTROTHERMIC FIRE ALARM.

Application filed May 12, 1925, Serial No. 23,840, and in Italy and Great Britain May 13, 1924.

This invention relates to new and useful improvements in electro-thermic fire alarms and has for its principal object the provision of an electric alarm mechanism which includes a normally open electrical circuit and means for closing the circuit responsive to changes in atmospheric temperatures.

In the form of my invention as disclosed in the accompanying drawings:

10 Figure 1 is a vertical sectional view of the mechanism.

Figure 2 is a detailed sectional view taken on line 2—2 of Figure 1.

15 Figure 3 is a horizontal sectional view showing particularly the means for mounting the terminals, and

Figure 4 is a front elevation.

Referring to the drawings, my invention comprises a box or casing 1 of very thin 20 metal which is secured to the underside of a dial casing 2. The casing 2 includes a base portion 3 having an opening 4 therein. A standard 5 extends upwardly from the base portion 3 and supports a tubular dial 25 casing 6. Disposed within the opening 4 and forming a closure therefor is a flexible diaphragm 7, having an upwardly extended axially located seat 8. Journalled at its respective ends in the dial casing 6, and in

30 an insulating bushing 8^a in a metallic disc 8^b carried by the casing is a shaft 9 located directly above the seat 8 and having a pinion 10 thereon. The disc 8^b is insulated from the casing 6 by an insulating ring 21

35 interposed between a flange on the disc and the casing, and is secured to the casing by screws 21^a insulated from the casing by insulating washers 21^b and insulating bushings 21^c. A lever 11 is fulcrumed as at 40

to the casing 6 and carries a segmental rack 13 which engages the pinion 10. One arm of the lever 11 is pivotally connected as at 45 to the upper end of a rod 15, the lower end of the rod abutting the diaphragm 7

45 through the medium of the seat 8. A coil spring 16 has its outer end fixedly connected to the dial casing 6 by a screw 17 and has its other end fixedly connected to the shaft 9.

50 A normally open electrical circuit (not shown) includes two terminals 18 and 19, one of which is grounded on the metallic dial

casing 6 and the other of which is insulated therefrom. A metallic bracket 20 is mounted on the disc 8^b which is connected to the terminal 19 by means of a conductor 55 20^a. Journalled in this bracket is a normally stationary contact arm 22 provided with a contact projection 22^a. In this instance the contact arm 22 is in the nature of a pointer or hand and is fixed to a manually operable shaft 23 journalled in the bracket 20 whereby the hand may be turned to any desired angular position and retained in such adjusted position. The shaft 23 is co-axial with the shaft 9 and fixed to the 60 shaft 9 is a movable contact arm 24 provided with a contact screw 24^a, which is adapted to engage the relatively stationary contact projection 22^a, and thereby close the electric 65 alarm circuit.

70 It will be observed that I have provided an actuating means which includes a rod having one end pivotally connected to segmental lever 11 and its other end abutting the diaphragm 7, and the spring 16 is connected to the shaft 9 for serving the two 75 functions, viz, yieldably holding the movable arm 24 in relation to the fixed contact and yieldably holding the rod 15 in engagement with the diaphragm.

80 In operation, as the temperature in a room increases due to a fire or the like, the air within the casing 1 will expand and deflect the diaphragm upwardly. This will elevate the rod 15 which will oscillate the 85 lever 11. As a result, shaft 9 will be rotated and consequently the movable contact arm 24 will be correspondingly rotated. The contact 24^a will then contact with the stationary contact 22^a and thereby close the 90 alarm circuit.

Having now particularly described and ascertained the nature of my said invention and in what manner the same is to be performed, I declare that what I claim is:

95 An electro-thermic alarm including in combination, a normally open alarm circuit including a fixed contact and a movable contact arm cooperating therewith, a shaft to which the movable arm is fixed, 100 and pressure operating means for actuating the shaft comprising a closed air

chamber having a diaphragm therein, a pinion fixed on the shaft, a pivoted lever having a segment engaging the pinion, a rod having one end pivotally connected to the lever and having its other end abutting the diaphragm whereby the rod will be moved longitudinally under the influence of the diaphragm,

and a spring connected to the shaft for yieldably holding the movable arm in spaced relation to the fixed contact and for yieldably holding said rod in engagement with the diaphragm. ¹⁰

Dated this 13th day of May, 1924.

PIETRO AMEGLIO.
